(57) **CLAIM**

The ornamental design for a tree and plant staking bar, as shown and described.

DESCRIPTION

FIG. 1 is a front perspective view of the tree and plant staking bar of the instant invention;

FIG. 2 is a rear perspective view thereof;

FIG. 3 is a left side view thereof;

FIG. 4 is a right side view thereof;

FIG. 5 is a front end view thereof;

FIG. 6 is a rear end view thereof;

FIG. 7 is a top view thereof;

FIG. 8 is a bottom view thereof; and,

FIG. 9 is a pictorial view thereof.

The broken lines are included, for the purpose of illustrating an environment of use and form no part of the claimed design.

1 Claim, 8 Drawing Sheets
